Assistant Examiner — Rodolfo Castro, Jr.

(57) **CLAIM**

The ornamental design for a car mount, substantially, as shown and described.

DESCRIPTION

FIG. 1 is an exploded rear perspective view of a car mount showing my new design;

FIG. 2 is a front perspective view of the car mount fully assembled;

FIG. 3 is a front elevation view of the car mount fully assembled;

FIG. 4 is another front elevation view of the car mount fully assembled in an alternate position;

FIG. 5 is a rear elevation view of the car mount fully assembled;

FIG. 6 is a rear elevation view of the front part of the car mount shown without the rear part;

FIG. 7 is a left side elevation view of the car mount fully assembled;

FIG. 8 is a right side elevation view of the car mount fully assembled;

FIG. 9 is a top plan view of the car mount fully assembled; and,

FIG. 10 is a bottom plan view of the car mount fully assembled.

Broken lines illustrate portions of the car mount that form no part of the claimed design.

1 Claim, 10 Drawing Sheets
